(57)

CLAIM

the ornamental design for a light fixture, as shown and described.

DESCRIPTION

FIG. 1 is a top perspective view showing our new design; FIG. 2 is a bottom perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a top perspective view of a second embodiment thereof; FIG. 10 is a bottom perspective view thereof; FIG. 11 is a front elevational view thereof; FIG. 12 is a rear elevational view thereof; FIG. 13 is a left side elevational view thereof; FIG. 14 is a right side elevational view thereof; FIG. 15 is a top plan view thereof; and, FIG. 16 is a bottom plan view thereof.
The break lines in FIGS. 1-6 and 9-14 are to indicate that the appearance of any portion of the light fixture between the break lines forms no part of the claimed design.
The broken lines in FIGS. 1-16 illustrate portions of the light fixture that form no part of the claimed design.
